(57) **CLAIM**

The ornamental design for a flat iron comb attachment, as shown and described.

DESCRIPTION

FIG. 1 is a top front perspective view of a flat iron comb attachment showing my new design;

FIG. 2 is a front elevation view thereof;

FIG. 3 is a rear elevation view thereof;

FIG. 4 is a right-side elevation view thereof; with a left-side elevation view being a mirror image of the right-side elevation view;

FIG. 5 is a top plan view thereof; and,

FIG. 6 is a bottom plan view thereof.

The line shading on the comb, bottom surfaces, and top surfaces depicts flat surfaces. The line shading on the top bolt ridges depicts curved surfaces. The broken lines shown in the drawings depict portions of the article that form no part of the claimed design.
